UNITED STATES PATENT OFFICE.

CATO HAARBERG, OF KENT, WASHINGTON.

DOOR LATCH.

Application filed June 2, 1926. Serial No. 113,227.

This invention relates to improvements in door latches of the pivoted bolt type, and while in its broader aspects the present invention comprehends a latch which may have 5 a wide range of utility, it is particularly concerned with pivoted bolt latches for swinging closure elements.

An object of the invention is to provide a latch of this character which may be conveniently locked against operation, a latch which is automatically acting when the closure is swung to, a latch of simple, practical construction, which will be rugged, durable and efficient in use, which may be 15 manufactured with comparative economy, and which may be readily applied to a door or other closure element.

With the above noted and other objects in view, the invention consists in certain 20 novel features of construction and combinations and arrangements of parts, as will be more fully hereinafter set forth and pointed out in the claims. The invention may be more fully understood from the following 25 description in connection with the accompanying drawings, wherein—

Fig. 1 is a fragmentary vertical sectional view through a door, with my improved latch attached thereto, the dotted lines indicating the position of the bolt mechanism 30 when the latch is rocked on its pivot to disengage the bolt from the keeper.

Fig. 2 is a view similar to Fig. 1, but showing the latch locked against pivotal 35 movement.

Fig. 3 is a sectional plan view on the line 3—3 of Fig. 2.

Fig. 4 is a transverse sectional view on the line 4—4 of Fig. 2.

Fig. 5 is a view similar to Fig. 1, but illustrating a slightly modified type of latch.

Fig. 6 is a view similar to Fig. 5, but showing the latching bolt locked against pivotal movement.

Fig. 7 is a sectional plan view on the line 7—7 of Fig. 6.

Fig. 8 is a transverse sectional detail on the line 8—8 of Fig. 6.

Fig. 9 is a view similar to Fig. 1, but illustrating a further modified form of latch.

Figs. 10 and 11 are sectional plan views on the lines 10—10 and 11—11 respectively of Fig. 9.

Fig. 12 is a view in outside elevation of 55 the latch of Fig. 9.

Referring first to the form of door latch shown in Figs. 1 to 4, it will be noted that I have used the reference character 10 to indicate a closure frame, and the reference character 11 to indicate a closure hingedly mounted at one edge (not shown) and adapted to be latched to the frame. For convenience of description, the closure will be hereinafter referred to as the "door", and the closure frame, referred to as the "frame". 60

To the inner and outer faces of the door near the free edge thereof, are secured escutcheon plates 12 and 13 having aligned slots 14 and 15 therein which register with a bolt slot 16 in the door. Bearing brackets 65 17 fixed to the inner escutcheon plate 12 serve as a pivotal mounting for one arm 18 of the U-bolt 19. The latching bolt 21 is mounted to rock on the end of the arm 18, and is engaged by the other arm 20 of the 70 U-bolt 19.

A keeper 21 in the nature of an L-shaped bracket is secured to the frame 10, and is engageable in a notch 22 in the lower edge of the bolt 21^a. A coiled torsional spring 23 80 encircling the arm 18 of the U-bolt 19 bears against the intermediate portion of said bolt and maintains the pivoted bolt 21 spring pressed into engagement with the keeper 21^a.

It will be noted that the bolt 21 is formed 85 at its inner end with a camming face 24 which engages with the keeper 21^a to elevate the inner end of the bolt as the door is swung to closed position, and when the keeper has cleared the notch 22, the bolt will 90 be spring pressed into its latching position. Thus, the bolt latches automatically as the door is swung to closed position.

For effecting manual disengagement of the bolt from the keeper from the outside 95 of the door, the outer end of the bolt is provided with a handle member 25 facilitating the manual rocking of the bolt on its pivot 18. Means are also provided for selectively locking the bolt against pivotal movement 100 and consequently locking the door to the frame. This means includes a fork 26 integral with a plate 27 and offset therefrom. Plate 27 is pivoted at its lower end to the bottom of the outer escutcheon plate 13 as indicated at 28, and when swung from the position of Fig. 1 to the position of Fig. 2, the fork 26 straddles the outer end of the bolt closely adjacent an opening 29 therein. By passing the hasp 30 of a padlock 110

through the opening 29, such hasp will engage with the fork to prevent pivotal movement of the bolt 21.

In Figs. 5 to 8 inclusive, I have illustrated a slight modification of the latch in which different means are utilized for spring pressing the latch into engagement with its keeper and for locking the latching bolt against pivotal movement. Referring now to these figures, the pivoted bolt 35 extends through aligned slots in the door 11, and the inner and outer escutcheon plates 36, 37. The bolt is pivoted on a screw 38 which extends across the slot in the door. The inner end of the bolt is notched at 39 for engagement with a keeper 40 secured to the frame 10, and the bolt is spring pressed into engagement with the keeper by a coiled contractile spring 41 anchored to the outer end of the bolt, and to a staple or other suitable anchorage 42 on the outer face of the door. Bolt operating handles 43 are provided at both the inner and outer ends of the bolt 35.

The means for locking the bolt against rocking movement in this instance includes a channel piece 44 pivoted at 45 to the bolt on the inside of the door. Adjacent the channel piece, a pair of openings 46 are provided in the bolt. With the channel piece swung to the position of Fig. 5, the shackle 47 of the padlock 48 may be conveniently hung in the lower opening 46 and normal operation of the bolt may be had. If, however, the channel piece 44 is swung through approximately 90° to the position of Fig. 5, and the shackle of the padlock shifted into the upper opening 46, it will be seen that the channel member effectively blocks pivotal movement of the bolt. Any attempted rocking movement thereof to disengage it from the keeper, causes the shackle of the padlock to force the channel member against the inner escutcheon plate.

In Figs. 9 to 12 inclusive I have illustrated a further modification of the invention, in which the bolt 50 is in the nature of a relatively wide plate rocking in aligned slots 51 in the door 11 and the inner and outer escutcheon plates 52, 53. In this instance the escutcheon plates are connected by a U-bolt 54, the intermediate portion of which overlies the outer face of the outer escutcheon plate, and the legs of which pass through the inner escutcheon plate and are retained by nuts 55. The intermediate portion of the U-bolt 54 passes through an opening 55 in the latch 50 and serves as a pivot therefor.

A coiled contractile spring 56 anchored at 57 to the inside of the door and engaged at 58 with the inner portion of the latch 50, urges the latch into engagement with a keeper 59 secured to the frame 10. Oper-

ating handles 60 and 61 are provided at the inside and outside of the latch. In order to lock the latch against pivotal movement, it is merely necessary to pass the shackle 62 of a padlock 63 through an opening 64 in the lower edge of the outer end of the latch 50. This padlock engages the escutcheon plate 53 to prevent movement of the latch about its pivot 54. In the form of the inventions previously described, the slots in the escutcheon plates may serve as an effective stop to limit the spring pressed movement of the latching bolt when the bolt is not engaged with the keeper. In the form shown in Figs. 9 to 12, cross pins 75 secured to the latch engage the escutcheon plate to limit the spring pressed movement of the bolt when the door is opened.

While I have shown certain of the preferred embodiments of the invention, it will be evident that numerous changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. The combination with a closure frame and a swinging closure, of escutcheon plates secured to opposite faces of the closure near the free edge of the latter, said escutcheon plates and closure having aligned slots therein, a bolt pivoted intermediate its ends and extending through the slots, a keeper on the frame, spring means urging the bolt into engagement with the keeper, and means for selectively locking the bolt against pivotal movement, including a forked element pivoted to one of the escutcheon plates and adapted to straddle the bolt and be held against movement to inoperative position by a padlock shackle passed through the bolt.

2. The combination with a closure frame and a swinging closure, of escutcheon plates secured to opposite faces of the closure near the free edge of the latter, said escutcheon plates and closure having aligned slots therein, a bolt pivoted intermediate its ends and extending through the slots, a keeper on the frame, spring means urging the bolt into engagement with the keeper, and means for selectively locking the bolt against pivotal movement including a padlock hasp passed through an opening in the bolt adjacent one of the escutcheon plates, and means associated with said escutcheon plate and coacting with the shackle to prevent rocking of the bolt.

CATO HAARBERG.
